CLAIM

The ornamental design for a car charger for smokers' accessories, as shown and described.

DESCRIPTION

FIG. 1 is a front, top, and left side perspective view of a car charger for smokers' accessories;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines depict portions of the car charger for smokers' accessories that form no part of the claimed design.

1 Claim, 7 Drawing Sheets
